[57] CLAIM

The ornamental design for a wall mountable light shade, as shown and described.

DESCRIPTION

FIG. 1 is a perspective view taken from the left, bottom and front, showing my new design;

FIG. 2 is a left side elevational view thereof, the right side being the mirror image of the left side shown;

FIG. 3 is a front elevational view thereof;

FIG. 4 is a top plan view thereof; and,

FIG. 5 is a bottom plan view thereof.

The broken line representation of an attachment hole in FIG. 2 and a decorative button in FIG. 3. are for purposes of illustration only.
